UNITED STATES PATENT OFFICE

2,288,835

COIN CHUTE

William Patzer and Walter A. Tratsch,
Chicago, Ill.

Application July 27, 1939, Serial No. 286,789

1 Claim. (CL 194—100)

This invention relates to coin testing devices and has as its principal object the provision of a means for compensating for variations in magnetic influence of the testing devices, which will be simple in structure, economical in manufacture and highly efficient in use.

Other objects, advantages and economies peculiar to the invention relate to certain details of construction, as well as the arrangement and operation of the parts hereinafter described in view of the annexed drawing, in which:

Fig. 1 is a perspective of a testing unit;

Fig. 2 is a vertical section along line 2—2 of Fig. 1;

Fig. 3 is an inside elevation of the gate showing the improved runway;

Fig. 4 is a fragmentary elevation of the inside wall of the chute; while

Fig. 5 is a fragmentary section through the chute along line 5—5 of Fig. 4.

The present invention provides improvements which are illustrated in conjunction with a coin chute of the type described in detail in our copending application, Serial No. 266,582, filed April 7, 1939, such a chute including a main plate member 10 having opposite vertical edges 11 upset to provide end walls and provided with a gate 12 which is swung on a pivot rod 13 extending through ears 14 offset along the upper edge parts of the gate, and ears 15 offset along upper edge parts of the main plate. The gate is thus adapted to swing about a horizontal axis toward and away from the inner side of the plate 10 between the flanges 11.

An upper edge part 16 of the gate is offset to provide an entrance opening 17, in confrontation with the opposite portion of the main plate, which opening leads into the space between the gate and the main plate. This offset formation of the entrance-forming part 16 on the gate has a particular function in providing a scoop or enlarged area at the entrance in which a plurality of coin elements may collect to prevent jamming, the detailed operation and construction of this feature being particularly set forth and claimed in the aforesaid copending application and another copending application, Serial No. 250,679, filed January 13, 1939.

The space between the gate 12 and the inner surface of the main wall member 10 constitutes the main chute passage P, as indicated in Fig. 2, this passage, in so far as it actually confines the movement of the coin, terminating at the lower edge 12a of the gate just above a rebound anvil 18, which constitutes one of a plurality of testing

devices disposed in the chute below the entrance. This anvil is preferably of the type described and claimed in our United States Patent No. 2,159,117, and which anvil includes as one of its features an elongated ridge 18a inclined downwardly and against which the rim of a coin impinges to cause genuine coins (i. e. coins of genuine U. S. mintage, particularly five-cent pieces) to rebound in a certain manner over a reject opening 19 and a separator 20 and into an acceptance opening 21 on the far side of the selector from the anvil. The ridge 18a, it may be remarked, in effect dents either momentarily or permanently certain spurious coin elements, causing the same to lose energy otherwise necessary to carry them into the opening 21, so that such elements drop into the reject opening 19.

In order for the testing means or anvil 18 to function properly and reliably, it is necessary that 20 the coin elements be directed or gravitated thereagainst at a more or less uniform rate, and to this end one of the features of the present invention provides an adjustable runway 25 mounted preferably on the inner side of the gate 12 with its upper end disposed below the entrance opening 17 and its lower end 25a terminating in spaced relation above the anvil 18 so that genuine coin elements will leave the same and follow a certain trajectory toward the anvil. Since slight variations in the inclination of the runway 25 have a very definite effect upon the trajectory followed by the various coin elements in leaving the same, the present invention provides for adjusting the runway. To this end the runway 25 is pivotally mounted on the inside face of the gate 12 as at 26 at the upper end of the runway 25, the runway 25 being provided with locking means in the form of a screw 27 passed through an arcuate slot 28 formed in the gate 12 and threaded into the runway 25 at a point below the pivot 26. By loosening the screw 27, the lower end 25a of the runway may be raised or lowered as the circumstances require, the screw thereafter being turned up to lock the same in position.

In accordance with the foregoing arrangement, the main force of the impact of coins dropping on the runway is taken up at the pivot 26 which lies substantially beneath the entrance opening 17, and there is therefore little stress on the locking means 27, thus obviating the danger of jolting the runway out of adjusted position through repeated use.

Additional testing means which functions critically in cooperation with the runway and anvil 18, includes a permanent magnet 30 mounted

on the outside or back of the main plate 10, so that its poles are substantially opposite the lower end 25a of the runway, as illustrated in dotted lines in Figs. 1 and 4, and in full lines in Fig. 5. It should be observed that in Fig. 4 the gate is removed to expose the inner surface of the plate 10, and the runway would therefore not be seen, the same being indicated in its operative position by dotted lines to show its relation to the magnet.

Legitimate coin elements are influenced in a certain manner by the magnet 30 so as to permit such coins to follow a certain trajectory, and the runway must therefore be adjusted more or less critically with respect to this testing means, as well as with respect to the anvil 18, the runway also being arranged so that coin elements which are not influenced by the magnet 30 will nevertheless follow a suitable but different trajectory than that of legitimate coins so that such spurious coin elements will come into engagement with the anvil 18 for passage into the reject opening 19.

A further testing means and one which constitutes an additional improvement in part of the present invention, is a feeler comprising an elongated wire finger 35 (Figs. 1 and 2) secured at its upper end in a weighted mounting member 36. This mounting is accomplished by providing a narrow cut in one vertical edge of the member 36 and disposing the upper end of the finger in the cut and thereafter crimping over the side walls 37 of the cut to clamp the finger in position. The weighted mounting member 36 is pivoted as at 38 in a bracket 39 secured to the outside of the gate close to the offset entrance-forming part 16 thereof, the pivot 38 being disposed eccentrically above the center of mass of the member 36, so that the bottom portions of the latter in which the finger is mounted will gravitate downwardly to project the offset end 35a of the finger through an opening 40 in the gate and across the passage P to engage the coin elements descending onto the runway 25.

The weighted carrying member 36 for the feeler is arranged with respect to its weight and pivotal mounting so as to render the finger yieldable to pressure of descending coins to the extent that the end portion 35a will be pushed out of the way while at the same time bearing against the side of the coin during its transit toward the runway, so that if the coin is apertured or has irregularly deep surface configurations, the end 35a of the feeler will arrest the coin. Coin elements which are too light to push the finger aside will also be arrested.

In order to clear the chute of coin elements which become jammed in the entrance 17 or which are arrested by the feeler 35, means is provided for moving the gate away from the plate 10 to widen the passage and open the same at its bottom by withdrawing the bottom-forming runway or ledge 25 from the opposite wall of plate 10. This means includes the provision of an operating lever 41 pivoted on the outside of the plate 10 and provided with an offset cam arm 42 which engages roller 43 on the gate and pivots the latter outwardly when the lever is depressed. It may be mentioned also that a roller 42a on the cam offset 42 also cams a sweep 44 out of its normal position for movement across the poles of the magnet to dislodge any coin elements which may be arrested by the same.

It is important to observe that the inner edge parts adjacent the crimps 37 on the weighted

feeler carrier 36, are spaced as at 45 (Fig. 2) from the opposite surface of the offset part 16 of the gate, and it will also be observed that the opening 40 for the feeler is elongated vertically. As a result of the foregoing arrangement, the end 35a of the feeler normally bears against the opposite wall 10 of the main plate and will remain in contact with the latter during a small part of the initial opening movement of the gate so that it will be impossible to repeatedly oscillate the gate in very short strokes to cause dislodgement of arrested coin elements so that the same may continue down the runway 25, since by such manipulation the runway 25 would not be moved far enough away from the opposite wall to open the passage sufficiently to permit the coins to escape. Therefore, the gate must be opened a predetermined distance adequate to move the runway 25 far enough away from the main mounting plate so that the passage will be opened substantially, and when the gate has moved this initial distance, the upper edge part 40a of the feeler opening 40 will bear against the feeler or finger and carry the latter with it so as to withdraw the end 35a from the passage and release any arrested coins, and by the time the feeler is thus withdrawn, the passage has been definitely opened.

Arrested coin elements which are released either from the influence of the feeler 35 or the magnet 30, or from the collecting effect of the enlarged entrance structure 17, will gravitate straight down into a discharge chute 46 which has its lower discharge end 47 disposed opposite the reject exit 19. Thus, all of the coin elements which are cleared from the chute are returned to the exit 19. Entrance of such released coin elements into the acceptance opening 21 is prevented by the offset inner wall part 46a of the reject chute which is disposed in blocking relation to the acceptance passage and which passes through an opening in the main plate for attachment to the outside of the latter as at 48.

The gate 12 is disposed in its normally closed position by action of gravity and also by attraction of a thin keeper plate 49 by the magnet 30, the plate being secured to the outside of the gate and, in addition to providing a supplemental closing means, concentrates the field of force from the magnet across the lower end parts 25a of the runway where it is most effective.

Another feature of the novel runway structure is the provision therein of a relieved or cut-away portion 25b which lies beneath the entrance opening 17 and is of a width such that coin elements of less than a certain thickness will pass through the narrow opening defined by this relieved portion and the opposite surface of the main mounting plate, and hence pass directly into the reject chute 46.

The various advantages and objects of the invention may be accomplished by modifications of the particular embodiment specifically described herein, and it is intended that the appended claim shall include all equivalent arrangements fairly coming within their call.

Having thus described our invention, what we claim as new and desire to protect by Letters Patent is:

In a coin chute provided with an entrance opening and having an open side wall and including a magnetic testing means on the wall opposite said open side wall for affecting the travel of coins along a predetermined trajectory, the combination of a scavenger gate pivotally

mounted in said coin chute and normally closing said open side wall, a runway carried by said gate, pin means pivotally mounting said runway on said gate beneath the entrance opening with the free end portion of said runway disposed at a point of declination adjacent said magnetic testing means, and means for securing said runway in adjusted position of declination relative to said pin means to regulate the speed of travel

of coins over said runway compensatory to the magnetic quality of said magnet testing means, said means including an arcuate slot formed in said gate and scribed on a radius from said pin means, and a headed locking means extending through said arcuate slot and having threaded connection with said runway.
